CHESTER M. MACCHESNEY, OF CHICAGO, ILLINOIS, ASSIGNOR TO ACME STEEL COMPANY, OF CHICAGO, ILLINOIS, A CORPORATION OF ILLINOIS.

METHOD OF MAKING EXPANDED METAL FENCES

Application filed August 7, 1929. Serial No. 384,225.

This invention relates to improvements in fences and its purpose is to provide a novel method of slitting and expanding a sheet of metal to form fencing. Heretofore, thin metal sheets have been provided with longitudinal slits and then expanded by stretching them edgewise to form a reticulated metal sheet adapted for use as metal lath and the like but these expanded sheets have not been adapted for use as fencing and no method has been known for expanding a metal sheet in a manner adapted to produce a reticulated metal sheet suitable for fencing purposes. The principal object of the invention is to provide an improved method of expanding a metal sheet to form a reticulated sheet suitable for fencing. Another object of the invention is to provide an improved method of forming an expanded metal fence having meshes which are relatively small along the lower edge of the fence and which increase progressively in size toward the top edge thereof. Another object of the invention is to provide an improved method of forming an expanded metal fence having upper and lower edges extending parallel to each other and devoid of irregularities due to the operation of expanding the metal from which the fencing is formed. Still another object of the invention is to provide an improved method of expanding a metal sheet in order to produce a perforated member adapted for fencing purposes and having meshes of varying size formed by the operation of expanding the metal sheet. A further object of the invention is to provide an improved method of forming expanded metal fencing comprising novel means for compensating for irregularities in the structure of the expanded sheet produced by the operation of expanding a metal sheet having slits therein of varying length. Other objects relate to various features of the improved metal fencing and of the process employed in forming the same, which will appear more fully hereinafter.

The nature of the invention will be understood from the following specification taken with the accompanying drawings, in which one example and a modification of the

improved method are explained in connection with one embodiment, and a modification, of the improved metal fencing. In the drawings,

Fig. 1 shows a top plan view of a portion 55 of an elongated strip or sheet of metal which is provided with a plurality of series of longitudinal slits preliminary to being expanded transversely to the length of the slits;

Fig. 2 is a somewhat diagrammatic plan 60 view of a portion of the expanded metal sheet produced by stretching edgewise the slitted strip or sheet shown in Fig. 1;

Fig. 3 shows an enlarged elevation or plan view of a portion of the expanded sheet illustrated in Fig. 2, showing the progressive variation in the sizes of the meshes of the expanded sheet from one edge thereof toward the other;

Fig. 4 is a sectional view taken on the line 70 4-4 of Fig. 3;

Fig. 5 is a partial plan view or elevation of a portion of the expanded sheet shown in Figs. 2 and 3 after the walls or bars of the meshes which extend parallel to the edges 75 of the sheet have been shortened by twisting in order to compensate for the curvature of the sheet when initially expanded as shown in Fig. 2; and

Fig. 6 is a partial plan view or elevation 80 similar to that of Fig. 5, showing the horizontal bars or walls of the meshes as having been shortened by corrugating them instead of by twisting as in the form shown in Fig. 5.

In the practice of the present invention, 85 an elongated steel strip or sheet 10, of such gauge or thickness as will produce the desired stiffness in the resulting fencing, is first provided, by a shearing action or otherwise, with a plurality of series of longitudinal slits 11 90 which extend parallel to the edges of the strip and parallel to each other throughout the length of the strip or sheet. The slits 11 of one series 11^a overlap the ends of the slits of the next adjacent series of slits 11 in a 95 zone 12 and the slits of one series are staggered, transversely of the sheet, with respect to the slits of the next adjacent series so that the slits are relatively closed to each other in the overlapping zone 12 and are there sepa- 100

rated by relatively narrow bars or metal elements 13. In the zones 14, where the metal sheet 10 is sub-divided into parallel elements by one series of slits 11 only, there are formed 5 a number of metal bars or elements 15 which are of substantially twice the width of the bars or elements 13. The slits 11 increase in length from the lower edge 10^a of the sheet toward the upper edge 10^b thereof and this 10 variation in length is preferably made to take place progressively so that the zones 14 between the ends of the slits of alternate series have a shape like that of a cross-section of a truncated cone, and the zones 13 in which 15 the slits 11 overlap increase progressively in width from the bottom of the sheet upwardly, giving them a form like that of a cross-section of an inverted truncated cone. As will be seen from an inspection of Fig. 1, the slits 11 20 of one series are in longitudinal alignment with the slits of alternate series throughout the length of the sheet. These slits extend completely through the sheet or strip 10 and they furnish means by which the sheet may 25 be permitted to expand transversely for the purpose of forming a porous or reticulated member suitable for fencing purposes.

The next step in the operation of forming the expanded metal fence is to apply pressure 30 to the sheet 10 for the purpose of expanding it laterally in a direction transverse to the length of the slits 11. This may be done by any suitable means known in the art and it results in the formation of a reticulated metal 35 sheet 16 having the form shown in Fig. 2, wherein the walls or bars separating the adjacent meshes are, for the sake of clearness, shown diagrammatically as single lines. These meshes 17 which are formed in the expanded sheet 16 are substantially diamond-shaped in form except that the upper and lower apices of the meshes are substantially flat instead of being pointed. The converging walls of each mesh 17 are formed by the 40 bars or elements 13 of the sheet 10 which are formed by the overlapping of the slits 11 of adjacent series and at the upper and lower corners or apices of each mesh, these diagonal walls or bars 13 are united with each other, 45 and with similar diagonal walls of adjacent meshes, by the connecting bars 15 formed by those portions of the slits 11 which lie in the zones 14. Since the slits 11 vary in length 50 from one edge of the sheet 10 to the other, the result of the expansion is to form meshes 55 17 which increase progressively in area from the bottom of the expanded sheet 16 to the top thereof, while at the same time the bars 15 which connect adjacent meshes longitudinally of the sheet decrease in length progressively from the bottom of the expanded sheet 60 upwardly. The longitudinal bars or metal elements 15^a which extend along the extreme upper and lower edges of the sheet 10, do not 65 tend to partake of the regular formation or

angularity which is assumed by the bars or elements 13 when the sheet is expanded, so that these elements are ordinarily bowed upwardly and downwardly along the edge of the expanded sheet, as shown in Fig. 2, forming a plurality of irregular convolutions 18. By reason of the fact that the slits 11 increase in length progressively toward the top edge of the sheet 10, the expansion of this sheet by exerting tension thereon transversely, results 70 in a greater contraction of the sheet longitudinally along its upper edge than takes place along its lower edge and this variation in the extent of the contraction makes itself apparent in a progressive manner from one longitudinal edge of the sheet to the other so that the expanded sheet 16 has a longitudinal curvature in its own plane and the lower edge 16^a and the upper edge 16^b thereof are curved, 75 with all intermediate portions assuming a 80 corresponding curvature of varying degree.

While it is important in the manufacture of fencing to provide meshes which are of relatively small size along the lower edge of the fence, for the purpose of confining relatively small animals, poultry and the like, and to provide relatively large meshes in the upper part of the fence, the expanded sheet 16 shown in Fig. 2, while embodying these 85 advantages so far as the relative sizes of the meshes are concerned, is not well adapted for fencing purposes because of its curvature, and the next step in the improved method of forming the fence consists in treating the expanded sheet 16 to compensate for the curvature resulting from the variation of the sizes of the meshes in order that the upper and lower edges of the fence will extend horizontally and parallel to each other. This is accomplished by operating upon the connecting 90 bars or elements 15 in order to shorten them progressively from the top edge of the fence downwardly, the ratio of the increase of this contraction being proportional to the divergence of the zones 14, shown in Fig. 3, which 95 mark the boundaries of the ends of the elements 15 which extend lengthwise of the expanded sheet. According to the preferred method, this contraction of the bars or elements 15 which form the longitudinal and substantially parallel walls of the meshes 17, 100 is effected by twisting these bars or elements 15 about their own axes to form twisted members 15^b having the form shown in Fig. 5. This twisting operation may be effected by 105 gripping an intermediate part of each element 15 and then revolving it about its own axis until the desired degree of shortening 110 has been effected. By suitable means, the twisting operation upon the elements 15 in the same zone 14^a may be so regulated and correlated that the expanded sheet is contracted 115 longitudinally with the extent of contraction increasing progressively from the top edge 120 of the expanded sheet downwardly, until a 125 130

final form of expanded sheet 20 is obtained wherein the upper and lower edges of the sheet extend horizontally and parallel to each other while the ends of the sheet are likewise 5 parallel but vertical. In conjunction with the feature of contracting the bars or elements 15 by twisting operations, the bars or elements 18 along the upper and lower edges of the expanded sheet 16 are similarly contracted by twisting operations to form twisted elements 15^c which align with each other along each edge of the fence and extend parallel to the similar aligning elements along the opposite edge of the fence. By this 10 means, the curvature due to expansion is compensated for so that the resulting expanded metal sheet 20 has the desired variation in the sizes of the meshes in combination with the desired parallel arrangement of 15 the upper and lower edges thereof and the desired horizontal positions of the axes of the various meshes 17.

Another method of contracting the sheet 16 to compensate for the curvature imparted thereto by expansion of the slotted sheet, is illustrated in Fig. 6, where the final form of the expanded sheet 21 is shown as having been produced from the form shown in Figs. 2 and 3 by corrugating the elements 15 to 20 form a series of bars 15^d which are corrugated transversely and thereby shortened longitudinally of the sheet. The number of corrugations in the bars or elements 15^d increases from the top edge of the sheet downwardly 25 with the result that the extent of contraction increases progressively toward the lower edge of the expanded sheet. In a similar way, the curved convolutions formed by the elements which are bowed outwardly along the upper 30 and lower edges of the sheet, as shown in Fig. 2, are contracted by corrugating operations to form horizontally corrugated elements 15^e along the upper and lower edges of the expanded sheet, as shown in Fig. 6.

45 The improved expanded metal fence formed by the novel method of the present invention has the advantage that it may be formed at relatively small cost from sheet steel or the like having great strength and the resulting 50 product is an integral construction, in which all of the elements of the reticulated fence are united by integral joints. The twisting or corrugating operations which are employed to compensate for the longitudinal curvature 55 in the plane of the sheet which is normally produced by the operation of expansion, when the slits vary in length from one edge of the sheet to the other, serve not only to produce the desired parallel arrangement of the 60 meshes and of the upper and lower edges of the sheet, but also to strengthen the sheet and give it additional resistance to transverse bending. After the expanded metal sheet has 65 been formed as shown in Fig. 5 or Fig. 6, it is preferably subjected to a final operation

which consists in passing it through a suitable bath whereby there is deposited upon the expanded sheet a galvanizing or other protective coating which protects it against rust.

Although certain examples of the improved method and two embodiments of the improved fence produced by that method have been explained in connection with the accompanying drawings by way of illustration, it will be understood that the method may be practiced in various ways and that the improved fence may be constructed in various forms within the scope of the appended claims.

I claim:

1. The method of forming expanded metal fencing which comprises the operations of providing a metal sheet with a plurality of longitudinal slits, the slits adjacent one edge of said sheet being longer than those adjacent the other edge thereof, and then expanding 80 the metal sheet transversely to the slits.

2. The method of forming expanded metal fencing which comprises the operations of providing a metal sheet with a series of longitudinal slits decreasing in length progressively from one edge of the sheet toward the other, and then expanding the metal sheet 90 transversely to the slits.

3. The method of forming expanded metal fencing which consists in providing a metal sheet with a plurality of overlapping series of parallel slits, having the slits of each series increasing progressively in length from one edge of the sheet toward the other, and then expanding said sheet transversely to the 95 length of the slits.

4. The method of forming expanded metal fencing which comprises the operations of providing a metal sheet with a plurality of series of longitudinal parallel slits, having the slits of each series increasing in length progressively from one edge of the sheet towards the other and having the ends of the slits of each series overlapping the ends of the slits of two next adjacent series, and then expanding the sheet transversely to the length 105 of the slits.

5. The method of forming expanded metal fencing which comprises the operations of providing a metal sheet with a plurality of series of longitudinal slits, then expanding the metal sheet transversely to the slits to form an expanded sheet having a plurality of meshes therein, and then contracting the 110 walls of certain of said meshes.

6. The method of forming expanded metal fencing which comprises the operations of providing a metal sheet with a plurality of series of longitudinal slits, then expanding 125 the metal sheet transversely to the slits to form an expanded sheet having a plurality of meshes therein, and then contracting the walls of certain of said meshes along the edges of the expanded sheet to form longi- 130

tudinal edges on said sheet extending parallel to each other.

7. The method of forming expanded metal fencing which consists in providing a metal sheet with a plurality of transverse series of longitudinal parallel slits increasing in length progressively from one edge of the sheet toward the other and having the ends of the slits of each series overlapping the ends of 10 the slits of the next adjacent series, the extent of overlap increasing progressively from one edge of the sheet toward the other, then expanding said sheet transversely to the length of the slits to form a plurality of meshes 15 increasing in area from one side of the expanded sheet toward the other, and then contracting those walls of the meshes which extend longitudinally of the expanded sheet.

8. The method of forming expanded metal 20 fencing which consists in providing a metal sheet with a plurality of transverse series of longitudinal parallel slits increasing in length progressively from one edge of the sheet toward the other and having the ends of the 25 slits of each series overlapping the ends of the slits of the next adjacent series, the extent of overlap increasing progressively from one edge of the sheet toward the other, then expanding said sheet transversely to the 30 length of the slits to form a plurality of meshes increasing in area from one side of the expanded sheet toward the other, and then contracting to a progressively decreasing extent from said first-mentioned edge of 35 said sheet toward the other edge those walls of said meshes which extend substantially parallel to the longitudinal edges of the sheet.

9. The method of forming expanded metal fencing which comprises the operations of 40 providing a metal sheet with a plurality of longitudinal slits, the slits adjacent one longitudinal edge of each sheet being longer than those adjacent the other longitudinal edge thereof, then expanding the metal sheet 45 transversely to the slits to form meshes, and then contracting those walls of the meshes which extend longitudinally of the expanded sheet.

In testimony whereof, I have subscribed
50 my name.
